(57) **CLAIM**

What is claimed is the ornamental design for a beverage dispenser, as shown and described.

DESCRIPTION

FIG. 1 is a front top perspective view of a beverage dispenser showing my new design;

FIG. 2 is a rear bottom perspective view thereof;

FIG. 3 is a front elevational view thereof;

FIG. 4 is a right elevational view thereof;

FIG. 5 is a rear elevational view thereof;

FIG. 6 is a top plan view thereof;

FIG. 7 is a bottom plan view thereof; and,

FIG. 8 is a rear top perspective view thereof with the door in open position.

The broken lines in the drawing depict portions of the beverage dispenser that form no part of the claimed design.
